1 Claim. (Cl. 315—210)

This invention relates to a dimmer or illumination control device for discharge lamps and the like.

Present time dimmers for discharge lamps are usually comprised by a conduction controller including at least one semiconductor such as a silicon controlled rectifier element and a gate signal generator for providing a gate signal, usually in the form of an electric pulse, to the gate electrode of said rectifier element. For dimmers designed to control a relatively large number of discharge lamps, the gate signal generator is required to produce a gate pulse of large magnitude. Generally the gate signal generator includes a pulse generator or oscillator and a gate transformer connected between said pulse generator and the gate electrode of said semiconductor rectifier element. In order to produce a large gate pulse from the secondary winding of the gate transformer the resistance in series with the primary winding thereof should be decreased. Then the resultant impedance of the circuit of the primary winding becomes inductive and if a silicon controlled rectifier element is involved in series with the primary winding it becomes difficult to turn off this rectifier element. In other words, the pulse generator can not generate a satisfactory pulse and hence the discharge lamp can not be controlled in the desired manner.

It is an object of this invention to eliminate the above-mentioned defect.

Further object of this invention is to provide a pulse generator of large power which can efficiently control semiconductor dimmer. While the specification concludes with the claim particularly pointing out and distinctly claiming the subject matter which is regarded as this invention, it is believed that the invention will be better understood from the following description taken in connection with the accompanying drawing, in which

FIG. 1 shows a connection diagram of a prior dimmer for discharge lamps;

FIG. 2 shows waveforms of various components of the dimmer shown in FIG. 1; and

FIG. 3 shows a connection diagram of a dimmer for discharge lamps constructed in accordance with this invention.

Before describing this invention in detail an example of a prior art dimmer will be described hereunder by referring to FIG. 1. A conduction controller including a pair of parallel connected semiconductors, such as silicon controlled rectifier elements SCR_2 and SCR_3 of opposite polarities is connected between a source of alternating current represented by input terminals t_1 and t_2 and a suitable step-up autotransformer T_2 , the secondary side thereof being connected to a discharge lamp PL . Filaments of the discharge lamp are energized by separate filament transformer T_3 .

The gate signal generating circuit 2 generally includes a full wave bridge rectifier 1 comprised by four diodes D_1 , D_2 , D_3 and D_4 . Input terminals of the bridge rectifier are connected across said terminals t_1 and t_2 and a series circuit including a resistor R_1 , the primary winding L_1 of a gate transformer T_1 and a silicon controlled rectifier SCR_1 , poled as shown in FIG. 1, and another series circuit including a resistor R_3 and a Zener diode ZD_1 .

2

poled as shown, are connected in parallel across the output terminals A and B of the bridge rectifier. A resistor R_2 is connected across said primary winding L_1 . The anode of the Zener diode is connected to one base electrode B_2 of a unijunction transistor UJT through a resistor R_5 while the cathode of the Zener diode is connected to the other base electrode B_1 of the unijunction transistor through a resistor R_6 to constitute a relaxation oscillator. The junction between the base electrode B_1 and the resistor R_6 is connected to the gate electrode of the silicon controlled rectifier SCR_1 . In parallel with the Zener diode ZD_1 is connected a series circuit comprising a resistor R_4 , a variable resistor VR and a condenser C , the junction between the variable resistor VR and the condenser C being connected to the emitter electrode E of the unijunction transistor UJT. Secondary windings L_2 and L_3 of the transformer T_1 are respectively connected across the gate and cathode electrodes of the silicon controlled rectifier elements SCR_2 and SCR_3 and diodes D_5 and D_6 are respectively connected across said secondary windings.

The magnitude of the output voltage of the full wave rectifier 1 at the right hand terminal of the resistor R_3 is made constant by the action of the Zener diode ZD_1 and is then utilized to charge the condenser C through resistors R_4 and VR . When the terminal voltage of the condenser C exceeds a predetermined value the unijunction transistor UJT will conduct momentarily to produce a pulse, as shown by FIG. 2b, across the resistor R_6 . Thus, it will be seen that the phase of this pulse is determined by the time constant of a circuit including resistors R_4 , VR and the condenser C so that it can be suitably varied by the adjustment of the variable resistor VR .

The gate signal generating circuit 2 operates as follows:

Alternating current voltage supplied to input terminals t_1 and t_2 is rectified by the full wave rectifier 1 to produce a pulsating voltage as shown by FIG. 2a across output terminals A and B. As stated above the relaxation oscillator comprising the unijunction transistor UJT acts to produce a pulse signal 1 as shown by FIG. 2b, which is applied across the gate and cathode electrodes of the silicon controlled rectifier element SCR_1 to trigger it whereby the primary winding L_1 of the gate transformer T_1 is energized by a pulsating current indicated by FIG. 2c. As a result a voltage indicated by FIG. 2d will be induced in the secondary windings L_2 and L_3 of the gate transformer T_1 .

As is well known in the art the silicon controlled rectifier elements SCR_2 and SCR_3 of the conduction controller are rendered conductive when the gate voltage d induced in the secondary windings L_2 and L_3 exceeds their threshold value. Since their conduction period during successive half cycles is determined by the phase of the pulse b shown in FIG. 2 the current supplied to the discharge lamp PL can be easily controlled by varying the variable resistor VR .

It is obvious that dimmers adapted to control many discharge lamps and the like loads require semiconductor controlled rectifier elements of large capacity so that large gate signals should be generated to operate these rectifier elements. To meet this requirement it is necessary to reduce the magnitude of the resistance R_1 connected in series with the primary winding L_1 of the gate transformer T_1 to increase the voltage induced in its secondary windings.

Decrease in the magnitude of said resistor R_1 , however, will make inductive the resultant impedance of the circuit including R_1 , R_2 , L_1 and SCR_1 . It was found that the silicon controlled rectifier SCR_1 connected in series with the primary winding often fails to cut-off its

current owing to such inductive impedance, thus providing unsatisfactory illuminating control.

This invention contemplates to eliminate the above-mentioned defect by substituting a diode for the resistor R_2 which is connected in parallel with the primary winding L_1 of the gate transformer T_1 .

More particularly, as shown in FIG. 3, a diode D_7 is connected across the primary winding L_1 of the gate transformer with the polarity indicated. Thus, when it is intended to change the silicon controlled rectifier from conductive state to non-conductive state the current which tends to flow through the primary winding L_1 by the action of said increased inductive impedance is by-passed through the diode D_7 so that the silicon controlled rectifier element SCR_1 is positively rendered non-conductive.

Since other components of FIG. 3 are quite identical with those designated by the same reference characters in FIG. 1, description thereof is believed unnecessary.

Thus, even in large dimmers for energizing relatively large number of lamps, by merely substituting a simple diode D_7 for a resistor R_2 connected across the primary winding of a gate transformer T_1 of the prior gate signal generating circuit 2 it is possible to provide sufficiently large gate pulses for the controlled rectifier elements contained in the conduction controller, thus assuring positive operation of the dimmer.

Although in the above described embodiment there has been shown a conduction controller comprising a pair of parallel connected silicon controlled rectifier elements of opposite polarities, it will be understood to those skilled in the art that the conduction controller may comprise four diodes connected in a bridge and one silicon controlled rectifier element connected between diagonals of the bridge.

While the invention has been explained by describing a particular embodiment thereof, it will be apparent that improvements and modifications may be made without departing from the scope of the invention as defined in the appended claim.

What is claimed is:

A dimmer circuit comprising
a plurality of discharge lamps,
a source of alternating current,
a conduction controller including
a first silicon controlled rectifier element connected between said source of alternating current and said discharge lamps,
and a gate signal generator adapted to supply a gate signal to said first silicon controlled rectifier element,
said gate signal generator including

a rectifier to rectify the alternating current voltage of said source,
a pulse oscillator for generating electric pulses comprising
a unijunction transistor supplied with the output of said rectifier,
a circuit connected across the output terminals of said rectifier and including in series
a primary winding of a gate transformer,
a resistor of relatively low value compared to the impedance of said primary winding,
and a second silicon controlled semiconductor rectifier element,
said electric pulses being applied to the gate electrode of said second silicon controlled rectifier element to repetitively trigger and cut-off said second silicon controlled rectifier element
means to supply the output of a secondary winding of said gate transformer to the gate electrode of said first silicon controlled rectifier element of said conduction controller,
and a diode means of polarity opposite to that of said second silicon controlled rectifier element and connected in parallel with said primary of said gate transformer and in series with said second silicon controlled rectifier element for passing therethrough the current which tends to flow through said primary winding due to its inductive impedance when said second silicon controlled rectifier element is cut-off in response to a pulse from said pulse oscillator, thereby causing a positive cut-off action.
